(57) **CLAIM**

The ornamental design for a case for portable computers and mobile telephones, as shown and described.

DESCRIPTION

1.-3. Case for portable computers and mobile telephones

1.1 is a Top Left Front Perspective

1.2 is a Top Right Front Perspective

1.3 is a Bottom Perspective

1.4 is a Front Elevational

1.5 is a Rear Elevational

1.6 is a Top Plan

1.7 is a Bottom Plan

1.8 is a Left Side Elevational

1.9 is a Right Side Elevational

2.1 is a Top Left Front Perspective

2.2 is a Top Right Front Perspective

2.3 is a Bottom Perspective

2.4 is a Front Elevational

2.5 is a Rear Elevational

2.6 is a Top Plan

2.7 is a Bottom Plan

2.8 is a Left Side Elevational

2.9 is a Right Side Elevational

3.1 is a Top Left Front Perspective

3.2 is a Top Right Front Perspective

3.3 is a Bottom Perspective

3.4 is a Front Elevational

3.5 is a Rear Elevational

3.6 is a Top Plan

3.7 is a Bottom Plan

3.8 is a Left Side Elevational

3.9 is a Right Side Elevational

1 Claim, 27 Drawing Sheets
